ATTORNEY

UNITED STATES PATENT OFFICE

CHARLES FLEISCHER, OF BROOKLYN, NEW YORK, ASSIGNOR TO J. FRANK MEYER, OF CHICAGO, ILLINOIS

COIN CONTROLLED SWITCH

Application filed May 8, 1932. Serial No. 276,088.

This invention relates to electric switches, and has particular reference to a coin controlled switch which while not exclusively restricted to such use, is especially designed to be employed in connection with a vending machine of the type set forth in U. S. Letters Patent No. 1,770,305, dated July 8, 1930.

One of the principal objects of the present invention is to provide an improved coin controlled electric switch which is arranged in a circuit including an electrically operated movable member, which switch comprises relatively movable spring engageable contacts, a coin releasable latch mechanism normally holding the contacts disengaged and a connection between the movable element and the latch mechanism which is operable to restore said latch mechanism to a normal condition when the movable element has completed a predetermined movement after the coin has released the latch mechanism.

The invention further comprehends a coin controlled electric switch of the character set forth and for the purpose specified which is comparatively simple in its construction and mode of operation, which is inexpensive to manufacture and which is thoroughly reliable and highly efficient in its purpose.

With the above recited and other objects in view, reference is had to the following description and accompanying drawings, in which there is exhibited one example or embodiment of the invention, while the claims define the actual scope of the same.

35 In the drawings:

Figure 1 is a view of the switch illustrating the same in its normal opened condition.

Figure 2 is an enlarged fragmentary view illustrating the same in its closed condition.

40 Figure 3 is a sectional view taken approximately on the line 3-3 of Figure 2.

Figure 4 is a horizontal sectional view taken approximately on the line 4-4 of Figure 2.

45 Figure 5 is a detail sectional view taken approximately on the line 5-5 of Figure 2.

Figure 6 is a sectional view taken approximately on the line 6-6 of Figure 4.

50 Referring to the drawings by characters of reference, 10 and 11 designate respectively

a pair of contacts which are relatively movable and which for the purposes of illustration are shown as movable and stationary. The contact element 10 is carried by and insulated from a movable contact arm 12, while the stationary contact 11 is carried by and insulated from a stationary bracket 13, to which bracket the movable contact arm 12 is fulcrumed at 14. A spring 15 is connected at its opposite ends respectively to a lug 16 on the arm 12 and a lug 17 on the bracket 13 and functions to effect the engagement of the contacts 10 and 11. A latch mechanism is provided for holding the contacts 10 and 11 in spaced non-contacting position against the action of the spring 15. The latch mechanism includes a latch trigger 18 which is fulcrumed at 19 to the contact arm 12 and which is provided with a nose 20 for engagement with a shoulder 21 of a trigger retaining member 22. The trigger retaining member is carried by or forms part of the arm 23 of a lever 24 which is fulcrumed at 25 to the bracket 13. The latch trigger is provided with a trigger pin 26 which extends through the slotted portion 27 of a coin chute 28 so that the trigger pin is disposed in the path of movement of a coin 29 when the same is inserted in the upper end of the coin chute and moves gravitationally therethrough. The trigger is properly weighted so as to be over balanced by the coin of the proper denomination. The lever 24 is provided with an arm 30 which is connected by a rod 31 to a mechanism for oscillating the same. The mechanism for oscillating the rod 31 may be of any type but for the purposes of illustration this mechanism includes a crank 32 operatively connected with the shaft 33 of a worm wheel 34 which is adapted to be turned by a worm gear 35 on a shaft 36 which is operatively connected with the shaft 37 of a motor 38. The motor is arranged in a circuit which includes a feed wire 39 leading from the positive pole of the source of supply to the contact 10, the contact 11 being connected by a feed wire section 40 which leads to one pole of the motor. The opposite pole of the motor is connected by a return wire 41 to the negative pole of the source of supply.

In operation, with the switch parts in the position illustrated in Figure 1, it is obvious that a coin inserted in the coin chute and gravitating therethrough will strike the trigger pin 26 over balancing the latch trigger 18 to swing the nose 20 upwardly out of engagement with the shoulder 21 of the trigger retaining member 22. Immediately the spring 15 functions to swing the trigger arm 12 so as to engage the contact 10 with the contact 11, thereby completing the circuit to the motor 38. The movement of the switch arm 12 under the influence of the spring moves the nose 20 of the latch trigger to the left in Figure 2 beyond the stop shoulder 21, the nose riding on the upwardly offset arcuate surface 42 of the member 22. The shaft 37 turning the shaft 36 obviously through the worm gear and worm wheel 34 and crank 32 reciprocates or oscillates the rod 31 in the direction indicated by the arrow in Figure 1, thereby swinging the upper arm 23 of the lever 24 to the left or in a counter clockwise direction to the dotted line position illustrated in Figure 2. This causes the stop shoulder 21 to again move past the nose 20 which then drops onto the upper arcuate surface 43 of the member 22. The return movement of the rod 31 swings the arm 23 of the lever 24 in the opposite direction, the nose 20 of the latch trigger 18 riding on the surface 43 until the shoulder 21 contacts with the nose 20. The member 22 continuing its movement shifts the latch trigger therewith and swings the contact arm 12 against the action of the spring 15 by momentum until the contacts 10 and 11 are separated or disengaged to break the circuit. Obviously the coin 29 after striking the trigger pin 26 is deflected and descends past the pin into a suitable coin receptacle not shown.

From the foregoing, it will thus be seen that a coin controlled electric switch has been devised by virtue of which an electric circuit including an electrically operated moving element may by the proper presentation of the coin, effect the closing of the circuit until the moving element has performed a certain function, after which the moving element restores the switch to its normal opened condition for breaking the circuit.

What is claimed is:

1. In a circuit including an electrically operable element, a controlling switch for said circuit comprising a pair of relatively movable contacts, means tending to effect engagement of said contacts constantly, a retaining element adjacent said contacts, a latch on one of said contacts and engaging said retaining element for normally holding said contacts apart, a release arm rigidly secured to said latch, and means operatively connecting said retaining element with said electrically operable element for actuating said retaining element to reestablish operative en-

gagement with said latch to reopen said switch subsequent to the release of said latch from said retaining element.

2. In a circuit including an electrically operable element, a controlling switch for said circuit comprising a fixed contact and a movable contact, means tending to effect engagement of said contacts constantly, a retaining element adjacent said movable contact, a shoulder on the retaining element, a latch pivotally mounted on said movable contact and engaging the shoulder on said retaining element for normally holding said contacts apart, a release arm rigidly connected to said latch, and means operatively connecting said retaining element and said electrically operable element for actuating said retaining element to reopen said switch subsequent to the closing thereof by the release of said latch from said retaining element.

3. In a circuit including an electrically operable element, a controlling switch for said circuit comprising a fixed contact and a movable contact, means tending to effect engagement of said contacts constantly, a retaining element pivotally mounted adjacent said movable contact, a shoulder on the retaining element, a latch pivotally mounted on said movable contact and engaging the shoulder on said retaining element for normally holding said contacts apart, a release arm rigidly connected to said latch, and means operatively connecting said retaining element and said electrically operable element for actuating said retaining element to rock said retaining element about its pivot to reengage said latch and thereby actuate said movable contact to reopen said switch subsequent to the closing thereof by the release of said latch from said retaining element.

4. In a circuit including an electrically operable element, a controlling switch for said circuit comprising a fixed contact and a movable contact pivotally mounted adjacent said fixed contact, means tending to effect engagement of said contacts constantly, a retaining element pivotally mounted adjacent said movable contact, a shoulder on said retaining element, a latch pivotally mounted on said movable contact and engaging the shoulder on said retaining element for normally holding said contacts apart, a release arm rigidly connected to said latch, and means operatively connecting said retaining element and said electrically operable element for actuating said retaining element to rock said retaining element about its pivot to reengage said latch and thereby rock said movable contact about its pivot to reopen said switch subsequent to the closing thereof by the release of said latch from said retaining element.

5. In a circuit including an electrically operable motor, a switch for controlling said circuit comprising a fixed contact and a movable contact, a stationary bracket supporting

the fixed contact, a lever supporting said movable contact and pivotally mounted on said stationary bracket, a spring tending to rock said lever about its pivot to effect engagement of said contacts, a retaining segment pivotally mounted on said stationary bracket, a latch pivotally mounted on said movable contact lever and normally engaging a shoulder on the retaining segment to hold the contacts apart, a releasing arm on said latch, a crank arm adapted for rotation by said motor, and a reach rod operatively connecting said crank and said retaining segment for rocking the retaining segment about its pivot to engage the latch and thereby rock the movable contact arm about its pivot to open the switch subsequent to the closing thereof by the release of the latch from the retaining segment.

20 Signed at Brooklyn, in the county of Kings and State of New York, this 7th day of April, A. D. 1928.

CHARLES FLEISCHER.
